UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

METHOD OF MAKING FLEXIBLE-BOLT BLANKS.

1,250,148.

Specification of Letters Patent. Patented Dec. 18, 1917.

Application filed February 23, 1915. Serial No. 10,013.

To all whom it may concern:

Be it known that I, ETHAN I. DODDS, a citizen of the United States, and a resident of Pittsburgh, in the county of Allegheny and State of Pennsylvania, have invented certain new and useful Improvements in Methods of Making Flexible-Bolt Blanks; and I do hereby declare the following to be a full, clear, and exact description of the invention, such as will enable others skilled in the art to which it appertains to make and use the same.

My invention relates to an improvement in method of making blanks for flexible track and other bolts, the object being to simplify the process of manufacturing the blanks whereby the cost of manufacture will be greatly reduced, and the output materially increased.

20 The invention consists in forming a long cylindrical bar with one or more slots extending throughout the length of the latter, twisting said bar while hot, cutting the bar into bolt blanks and heading and threading the blank to produce the bolt.

In the accompanying drawings, Figure 1 is a view of the slotted and twisted bar; Fig. 2 is a bolt blank cut from said bar; Fig. 3 is a view in section of the blank; Fig. 4 is a view of the blank headed; Fig. 5 is a view in transverse section of the headed blank and Fig. 6 is a view of the threaded bolt.

1 represents the bar from which the bolt blanks are cut. This bar is cylindrical and slotted throughout its length, the slots being closed without welding the walls thereof, and the slotted bar is then twisted throughout its length so that the slots will be in the form of spirals extending throughout the length of 49 that part of the bar from which the bolt blanks 2 are cut. The bar may be formed by rolling a flat bar between rolls as described in my pending application No. 2662 filed January 16th, 1915, or a cylindrical bar may 45 be slotted by a suitable tool or be passed between rolls having one or more cutting or grooving ribs.

I prefer to have two slots located at opposite sides of the bar, off the center of the latter, and passing more than half way through as shown in Figs. 3 and 5, although the number of slots employed is not essential.

I also prefer to roll the bar 1 from a slab or bar of metal as disclosed by me in the

application above referred to. After it has 55 been rolled or otherwise formed, and while hot, it is twisted from end to end, in any ordinary twisting machine. Bars thus treated or formed may be made in any mill and sold direct to bolt manufacturers.

To make bolts from the bar, the latter is reheated and is then fed to a machine which upsets the head and cuts off the blank as shown in Fig. 4.

By twisting the bar, the twist is constant 65 and uniform from end to end, and consequently is uniform in the blanks that are cut from the bar. The upsetting of the heads welds the wall slots at the head but leaves the walls of the slots in the shank disconnected thus permitting the shank to give or yield, as is well known in this type of bolt.

After the blanks have been cut from the bar, the threads are then either hot or cold 75 rolled, or they may be cut.

Having fully described my invention what I claim as new and desire to secure by Letters-Patent, is:—

1. The method herein described of making 80 flexible bolt blanks, consisting in providing a bar with a slot extending more than half way, but not wholly through the blank, closing the slot without welding the walls thereof, imparting cylindrical shape in cross section to the bar, and severing the bolt blanks 85 from the bar.

2. The method herein described of making 90 flexible bolt blanks consisting in providing a bar with a slot extending more than half way, but not wholly through the bar, closing the slot without welding the walls thereof, rounding the bar into cylindrical shape in cross section, and twisting the bar so as to carry the slot spirally around the same.

3. The method herein described of making 95 flexible bolt blanks consisting in providing a bar with slots extending throughout its length, and at opposite sides, each slot extending more than half way but not wholly through the bar, closing the slots without 100 welding the wall thereof, rounding the bar into cylindrical shape in cross-section and twisting the bar to carry the slots spirally around the same.

4. The method herein described of making 105 flexible bolts consisting in slotting a bar throughout its length at a plurality of points, each slot extending more than half way, but

not wholly through the bar, closing the slots without welding the walls thereof, rounding the bar into cylindrical shape in cross section, twisting the bar to carry the slots spirally around the same, and cutting the bar into bolt blanks.

In testimony whereof, I have signed this

specification in the presence of two subscribing witnesses.

ETHAN I. DODDS.
